UNITED STATES PATENT OFFICE.

JOHN J. SWEENEY, OF NEW YORK, N. Y.

WORK-TABLE GUARD FOR POWER-PRESSES.

1,137,550.

Specification of Letters Patent. Patented Apr. 27, 1915.

Application filed July 28, 1914. Serial No. 853,653.

To all whom it may concern:

Be it known that I, JOHN J. SWEENEY, a citizen of the United States, and a resident of the city of New York, borough of Manhattan, in the county and State of New York, have invented a new and Improved Work-Table Guard for Power-Presses, of which the following is a full, clear, and exact description.

10 This invention relates to automatic guards for use in connection with the work table of punching, stamping and other power presses, whereby the workman is prevented from keeping his hands in such position 15 with respect to the work that they are liable to be injured by the machine in performing its operation.

The invention has for its general objects 20 to improve and simplify the construction and operation of automatic guards of the character referred to so as to be reliable and efficient in use, comparatively simple and inexpensive to manufacture, and so designed as to be easily adjustable when the set of 25 the work table is changed.

A further object of the invention is the provision of a workman's guard in which the operating connections are mounted wholly under the work table so as to be out 30 of the way, and connected with the usual clutch pedal of the power press so that with the depression of the pedal for throwing on the power the guard will be also thrown into operation so as to cause the operator 35 to remove his hands from the danger zone of the machine.

With such objects in view, and others which will appear as the description proceeds, the invention comprises various novel 40 features of construction and arrangement of parts which will be set forth with particularity in the following description and claims appended hereto.

In the accompanying drawing, which 45 illustrates one embodiment of the invention and wherein similar characters of reference indicate corresponding parts in all the views, Figure 1 is a front view of a power press; Figs. 2 and 3 are side views showing different 50 positions of adjustment of the body of the press with respect to the base; Fig. 4 is a detail sectional view on the line 4—4, Fig. 1; Fig. 5 is a detail sectional view on the line 5—5, Fig. 1; and Fig. 6 is a detail sectional view on the line 6—6, Fig. 5.

Referring to the drawing, A designates the base or stand of the press, and B is the

body thereof which is so mounted as to assume different positions, as shown in Figs. 2 and 3, for facilitating the operation of the press, according to the work to be done. The operator's pedal 1 is united by suitable connections 2 and 3 with the clutch mechanism C, which is of usual construction and need not be described. The driving shaft 65 4 carries a pulley 5 and has a crank 6 which is connected by the reciprocatory punch, die or stamp head 7 which co-operates with work-holding means 8 on the operating table 9.

The protective device comprises an oscillatory guard C and operating means D. This guard includes a rod or shank 10 which swings along the front edge 11 of the work table 9, there being a guide 12 applied to the table so as to form a horizontal slot in which the rod 10 moves. On the upper end of the rod or shank 10 is an arcuate member, such as a wire frame 13, which will occupy a position in front of the work and die, as shown by dotted lines in Fig. 1 when the press is in operation, but when the die-carrying head 7 is raised the guard will move down from the broken-line to the full-line position, where it will remain as long as the power is off the press. The operating means D is located under the table 9 and comprises a depending arm 14 which has fulcrumed at 15 a swinging lever 16, the upper end of which is connected by a hinge joint 17 with the lower 90 end of the guard member 10. At a point below the pivot 15 is fulcrumed at 18 on the arm 14 a bell-crank lever 19 which has one arm 20 connected by a link 21 with the lever 16, while the other arm 22 is connected by a 95 rod 23 with the pedal 1. Any suitable adjusting means may be provided for connecting the rod 23 with the arm 22 of the bell-crank lever. In the present instance the arm 22 is shown with a plurality of openings 24 into any one of which is fastened a bolt 25 and on this bolt is a swiveled block 27 that has an opening 28 through which extends the rod 23, and a set-screw 29 in the block is adapted to engage the rod 23 and hold the same fixedly in place. The adjustment between the rod 23 and bell-crank lever is necessary in order to enable the press to be adjusted from the position shown in Fig. 2 to that shown in Fig. 3, or vice versa, 105 because, in this adjustment, the distance between the pedal 1 and the work table changes, as will be apparent by a comparison of the two figures, and also during this

adjustment the relation between the guard member 10 and lever 16 will change. The supporting arm 14 is connected with the work table 9 in such a manner as to be adjustable, as this arm will occupy an approximately vertical position at all times. Any suitable means may be employed for providing for this adjustment, but in the present instance a bracket 30 is fastened to the under side of the table, and between the lugs 31 of this bracket is engaged the hub 32 of the arm 14, and passing through the lugs and hub is a bolt 33 suitably fastened to the arm 14 so as to be rigid therewith. By loosening the nut 34 of the bolt 33 the arm 14 can be adjusted with respect to the table 9, and when adjusted in the proper position the bolt is tightened so that the arm will be rigid with respect to the table.

20 In operation the operator presses the pedal 1 when the work is in proper position on the table, and in doing this the power is thrown on. At the same time the bell-crank lever 19 is oscillated in a clockwise direction, Fig. 1, and this in turn through the link 21 and lever 16 carries the guard C from the full to the dotted line position, Fig. 1, and during the upward movement of the pedal by the spring 35, the guard is returned to 30 normal position.

From the foregoing description taken in connection with the accompanying drawing, the advantages of the construction and method of operation will be readily understood by those skilled in the art to which the invention appertains, and while I have described the device which I now consider to be the best embodiment thereof, I desire to have it understood that the device shown 35 is merely illustrative and that such changes may be made when desired as are within the scope of the appended claims.

Having thus described my invention, I claim as new and desire to secure by Letters Patent:

1. The combination of a machine including a work table, a working element coöperating therewith, and an operator's device for throwing on and off the power for the working element, with a guard mechanism carried wholly by the table and located under the same and having a member extending upwardly along the front of the table and movable back and forth, and a connection between the guard mechanism and the device for throwing on and off the power.

2. The combination of a power press including means for throwing on and off the power, a work table, with a guard movable back and forth and on the front of the table, and operating means carrying the guard and supported by the work table, and a connection including a motion multiply-

ing device between the guard operating means and the said means for throwing on and off the power.

3. The combination of a machine of the class described including a work table, and means for throwing on and off the power, with a swinging guard disposed at the front of the table, a supporting arm connected with and disposed under the table, a lever connected with the arm and carrying the guard, and motion multiplying means between the lever and the operating means of the machine.

4. A power press including a stationary base, a body adjustably mounted thereon, a work table on the body, a power-driven tool carrier disposed in coöperative relation with the table, a pedal on the base for throwing on and off the power, with a work table guard comprising means movable back and forth at the front of the table, an adjustable supporting arm mounted on the bottom of the table, a lever on the arm and to which the said means is hingedly connected, and a motion multiplying means between the pedal and lever for moving the latter back and forth.

5. A power press including a stationary base, a body adjustably mounted thereon, a work table on the body, a power-driven tool carrier disposed in coöperative relation with the table, a pedal on the base for throwing on and off the power, with a work table guard comprising means movable back and forth at the front of the table, an adjustable supporting arm mounted on the bottom of the table, a lever on the arm and to which the said means is hingedly connected, a second lever mounted on the said arm and connected with the first-mentioned lever, and an adjustable connection between the second lever and the pedal, whereby the latter operates the guard.

6. In a machine of the class described, the combination of a work table, an operating pedal, a rigid arm adjustably connected with the table and depending therefrom, a lever pivotally connected with the arm, a guard hingedly connected with the lever and movable back and forth at the front of the table, a second lever pivotally mounted on the arm, a link connecting the levers together, a rod connected with the pedal, and an adjustable connection between the rod and second lever.

In testimony whereof I have signed my name to this specification in the presence of two subscribing witnesses.

JOHN J. SWEENEY.
